UNITED STATES PATENT OFFICE.

THOMAS POWELL, OF CHESTER, PENNSYLVANIA.

FAN ATTACHMENT FOR ROCKING-CHAIRS.

SPECIFICATION forming part of Letters Patent No. 271,114, dated January 23, 1883.

Application filed May 22, 1882. (No model.)

To all whom it may concern:

Be it known that I, THOMAS POWELL, a citizen of the United States, and a resident of Chester, Delaware county, Pennsylvania, have 5 invented an Improved Fan Attachment for Rocking-Chairs, of which the following is a specification.

One object of my invention is to so construct the fan and the operating mechanism therefor 10 that the action will be direct and the parts few and of the simplest character, a further object being to cause a more extended swing of the fan than usual without the use of gearing.

15 In the accompanying drawings, Figure 1 is a perspective view of a rocking-chair with my improved fan attachment; and Figs. 2, 3, and 4, rear views of part of the attachment, showing the fan in different positions.

20 A is a rocking-chair of ordinary construction. To one of the side bars of the back of the chair is secured a rod, B, bent at the upper end to form a yoke, D, in which is journaled a shaft, a, secured to or forming part of 25 the fan F. A coiled spring, b, surrounds this shaft, one end of the spring bearing against the fan and the other end against the rod B, the tendency of this spring being to maintain the fan in the position shown in Fig. 2, or to 30 restore it to this position after it has been moved therefrom.

To the end of the shaft a is secured a lever, d, the short arm of which has a projection, e, and over the latter passes a cord, f, one end 35 of which is secured to the end of the long arm of the lever, the other end being secured to the long arm of a lever, G, pivoted to one of the rockers of the chair, so that its short arm will bear upon the floor. When the 40 chair is unoccupied and in its normal position the fan, fan-shaft, and lever d are in the positions shown in Fig. 2. When the chair is tilted backward, however, the lever G will be actuated, thus imparting a pull to the cord f, the first effect of this movement being to depress the short arm of the lever d, owing to the fact that the cord f passes over 45 the projection e on said arm. The shaft a is

thus caused to rotate, and the fan F swings inward and downward, as shown by the arrow, Fig. 2, the pull of the cord being exerted upon the short arm of the lever d until the latter assumes the position shown in Fig. 3, when the pull is transferred to the long arm of the lever, and the movement of the latter is continued until the parts reach the position shown in Fig. 4, the rocking-chair having then reached the extremity of its rearward movement. As the chair rocks forward the coiled spring b tends to restore the parts to 60 their original positions, as shown in Fig. 2, prior to a repetition of the operation.

It will be observed that the operating parts of the device are of the simplest character, and that the actions are direct and positive, 65 the device being therefore inexpensive in construction, easy to apply, and not liable to get out of order.

The formation of the projection e upon the short arm of the lever d is a valuable feature 70 of my invention, as it permits a movement of the lever d throughout about three-quarters of a circle, whereas if the cord f were connected directly to the end of an arm on the shaft the movement would be limited to less than half 75 of a circle, and the pull of the cord would be exerted at a disadvantage at and near the commencement and close of the movement.

I claim as my invention—

1. The combination of the chair with the 80 rod B, having a yoke, D, the fan F, its shaft a, spring b, and lever d, the lever G, hung to the rocker, and the cord f, connecting said levers d and G, as set forth.

2. The combination of the fan-shaft, the lever 85 d, the short arm of which has a projection, e, and the operating-cord f, connected to the long arm of the lever and adapted to pass over the projection e, as set forth.

In testimony whereof I have signed my name 90 to this specification in the presence of two subscribing witnesses.

THOMAS POWELL.
